UNITED STATES PATENT OFFICE.

GEORG HEIMANN, DECEASED, LATE OF CHARLOTTENBURG, GERMANY; BY ELSE HECHT, NÉE HEIMANN, ADMINISTRATRIX, OF CHARLOTTENBURG, GERMANY.

SEMIAUTOMATIC OR AUTOMATIC GRADED-SERVICE TELEPHONE SYSTEM.

Application filed August 16, 1921, Serial No. 492,760½, and in Austria December 30, 1918.

(GRANTED UNDER THE PROVISIONS OF THE ACT OF MARCH 3, 1921, 41 STAT. L., 1313.)

This invention relates to improvements in semi-automatic or automatic graded service telephone systems.

The object of this invention is to provide a telephone system with devices which for convenience of description will be referred to as "grading or zone switches", as they produce different effects upon the subscriber's meter according to the value of the connection established or they restrict the subscriber so that he can only make connections within a certain zone.

The motor magnet of the zone switch and the motor magnet of the selector switch with which the zone switch is associated may be connected in parallel. They therefore receive the same number of impulses and the switch movements produced by both magnets correspond exactly to each other. Hence it is apparent that the functions of both the zone and selector may be performed by the aid of a single motor magnet. For example the shaft of the selector switch may be provided in addition to the wipers for the talking connections with a device that closes different contacts of a zone switch according to the distance the selector switch is moved from its normal position. If a selector switch of the Strowger type is employed a ridge or collar may be arranged on the selector shaft which engages with a different set of contact springs of the zone switch at each step the shaft is lifted by the vertical motor magnet. If the amount of vertical movement imparted to the selector shaft corresponds to a non-permissible connection the movement of the contact springs of the zone switch produced by the collar of the selector shaft will affect circuits that disconnect the calling subscriber from the exchange selectors.

The contact springs of the zone switch affected by the collar of the selector shaft may also be arranged to act upon the meter circuit of the calling subscriber so as to cause the meter to register a higher or lower fee according to the value of the connection. A feature of this invention consists in providing zone switches which cause the meter to execute fewer or more steps according to the value of the connection and then to stop.

A zone switch of this kind is produced by building it up of two parts, a zone discrimi-

nating or impulse determining part (or "determining switch") which determines the 55 number of impulses to be delivered to a meter, and an impulse delivering part (or "delivering switch") which delivers the 60 number of impulses to the meter determined by the impulse determining part. The determining and delivering switches may be arranged to give any desired number of metering impulses.

The determining switch may consist of a 65 movable contact brush and a number of rows of fixed contacts corresponding to the number of different grades or zones of different values of the connections.

The delivering switch may also consist of a movable contact brush and of a row of 70 contacts over which the brush is caused to travel each time a conversation is to be registered.

Of the contacts in each row of fixed contacts on the determining switch fewer or 75 more are connected to the fixed contacts of the delivering switch according as the particular row corresponds to talking connections of a lower or higher value.

When a talking connection is established 80 the brush of the determining switch is moved to a certain one of its rows of fixed contacts and connects the contacts in this row to a source of current. A certain number of the contacts of the delivering switch 85 will thus be connected to the said current source and when, upon the registration of the connection, the brush of the delivering switch is caused to travel over its fixed contacts a certain number of impulses will be 90 delivered to the calling subscriber's meter.

The impulse delivering switch is so arranged that a momentary closure of a circuit at the moment a called subscriber responds, or at the moment an established connection is broken, will cause the switch to complete a cycle of functions and to return to its normal position so as to be in readiness for the registration of the next connection. This is accomplished by connecting the 100 motor magnet in the normal position of the delivering switch through a movable contact brush to a fixed contact, which leads to a point at which the motor magnet circuit is momentarily closed by the response of the 105 desired subscriber or at the finish of a con-

nexion. When the motor magnet circuit is thus closed, a spring is tensioned which exerts its force as soon as the momentarily closed circuit is reopened. The movable brush is then advanced to a fixed contact leading to an interrupter and this interrupter then imparts impulses to the motor magnet until the movable brush is moved a complete cycle and regains the fixed contact which represents the normal position of the movable brush and which is not in connection with the interrupter.

Shortly before reaching its normal position the impulse delivering switch may be arranged to brush past a mechanical locking device which holds the determining switch in its advanced position. This locking device is then caused to release the determining switch and to allow it to return to its normal position.

The invention is illustrated in the accompanying drawing in which Fig. 1 shows the circuits of a non-numerical switch or trunk finder and Fig. 2 the circuits of a connector of an automatic telephone exchange provided with the improved graded metering device.

Any number of group selectors may be introduced between the non-numerical switch Fig. 1 and the connector Fig. 2 but as the representation of the group selector is unnecessary for a clear understanding of this invention no group selectors are shown.

In Fig. 1 S is a subscriber's station which is furnished with an impulse transmitter IT and connected by wires a, b, and through the contacts 1, 2 of the test relay TR to the line relay LR of the trunk finder. OS₁ is an off-normal switch which is open only when the trunk finder is in its normal position and OS₂ is an off-normal switch the contacts 35, 40 of which are closed only in the normal position and the contact 34 of which is open only in the normal position. Z represents a subscriber's meter and T R₂ a relay by which the subscriber S may be disconnected from the selecting devices at the exchange.

In Fig. 2 CR is a line control relay which, whenever the connector is used, is switched into the circuit including the calling subscriber's loop. C R₁ is a change-over relay, R R a release relay, S M a side switch or "circuit changer" magnet, S₁, S₂, and S₃ are movable contacts controlled by the circuit changer magnet these contacts being shifted from their one stationary contact to the next each time a current impulse is sent through the circuit changer magnet, L M is the lifting magnet of the connector which, to simplify the description, is assumed to be of the well-known up-and-around type, R M is the rotary magnet, R M₁ the release magnet of the connector, T R₁ is a test relay, R R₁ a ringing current cut-off relay, R C R a ring-

ing control relay and OS₃, OS₄, off-normal switches that are open only in the normal position of the connector. E R is an energizing relay which closes the energizing circuit of the change over and release relays C R₁ and R R at a suitable moment and only when the connector is taken into use. a₂, b₂, c₂ are wires which connect the subscriber S to the fixed contacts in the contact banks of the group of connectors through which the subscriber is accessible. w₄, w₅, w₆ are the wipers of the connector.

The differential metering device or zone switch has three movable brushes k₁, k₂, k₃ and two motor magnets ZM₁ and ZM. The brushes are mounted on a shaft. Brushes k₂ and k₃ are fixed to each other and execute all movements in unison. They are driven by a ratchet and pawl, the latter being attached to an armature that turns on a pivot p and is moved forward by a spring f after each attraction of the armature by the magnet ZM. The brush k₁ is advanced in the direction of the arrow by a ratchet and pawl device (not shown) which is driven by the motor magnet ZM₁. At each step taken by the brush k₁ another row of contacts c a, c b, c c, is reached, these contacts being thus connected by the brush k₁ to the negative pole of the exchange battery.

It will be seen that in the contact rows c a, c b, c c, different numbers of contacts are connected to the contacts m¹, m², m³. The brush k₁, with its fixed contacts c a, c b, c c, and its magnet ZM₁, represent the zone discriminating or impulse determining switch and the brushes k₂, k₃ with their parts represent the impulse delivering switch.

If the contact arm k₁ is moved to either of the first three contact rows c a, c b, c c, only one contact m₁ of the delivering switch will be connected through c a and k₁ to the negative pole of the battery. If the contact k₁ is moved to the fourth, fifth or sixth contact row two contacts m₁, m₂ will be connected through contacts in the row and through k₁ to the battery. With k₁ on its seventh, eighth or ninth contact row the three contacts m₁, m₂, m₃ will be connected through c a, c b, c c, and k₁ to the battery. If, when the brush k₁ is on the first, second or third contact row, the brush k₂ is moved round a complete cycle so as to brush over all the contacts m¹, m², m³, one impulse will be delivered by the brush k₂ to the meter Z because only the first contact m¹ will be connected to the battery. With the brush k₁ on its fourth, fifth or sixth contact row two impulses would be delivered by k₂ and with k₁ on the seventh, eighth or ninth row three impulses would flow. Thus by a suitable number of fixed contacts in the contact rows of the determining switch and a suitable arrangement of the connections between these contacts and the contacts of the

delivering switch the possible connections of the system may be divided into a number of grades for which different charges are registered on the subscriber's meter.

- 5 In the example of the invention illustrated it is assumed that the subscriber is prevented from making any connections through the tenth row of contacts of the selector. Should the subscriber attempt to make such 10 a connection the brush k_1 will be moved to the tenth contact row ca, cb, cc which is connected through switch S_3 and wire e_1 with the disconnecting relay TR_2 . This relay will be energized when switch S_3 goes 15 into its second position and the subscriber will then be disconnected from the exchange selectors. The contacts controlled by relay TR_2 may be connected to a tone producing device when the disconnection of the line 20 takes place thus reminding the subscriber that the attempted call is non-permissible.

The brush k_3 of the delivering switch normally rests upon a contact segment s_1 which is connected to a contact 50. This contact 25 may be momentarily closed when the called subscriber responds as shown in the drawing but it may also be arranged to close when an established talking connection is broken down. The momentary closure of 30 50 results in a current impulse flowing from the negative pole through s_1, k_3, ZM to the positive pole of the exchange battery. The magnet ZM attracts its armature and tensions the spring f . When the impulse 35 ceases the spring f pulls the armature to its normal position and the pawl, which engaged with a new tooth of the ratchet wheel when the armature was attracted, then turns the brush k_3 forward into contact with the 40 segment s_2 . The segment s_2 being connected to an interrupter I_2 current impulses will now flow through ZM (from the negative pole through I_2, s_2, ZM to the positive pole) and the brush k_3 will be moved round till 45 it regains the segment s_1 , where it will stop until the contact 50 is closed by the establishing of another talking connection. As the brush k_2 is rigidly fixed to the brush k_3 it will be carried round with k_3 so as to 50 also execute a complete cycle or revolution.

The manner in which the system operates will now be explained.

The subscriber S desiring a connection 55 raises his receiver from its switchhook and connects the wires a, b in a well-known manner thus forming a loop through a, b through which current flows from the positive pole of the exchange battery through $LR, 2, b, S, a 1 LR$ to the negative pole. The line 60 relay LR then closes its contacts 3 and the turning magnet $R M$ (which acts upon the wipers, w_1, w_2, w_3 , in the well-known manner by a ratchet and pawl device) is alternatively energized and de-energized by current impulses flowing from the positive pole 65

through interrupter $I, RM, 3$ to the negative pole. The turning magnet thus causes the wipers w_1, w_2, w_3, w_7, w_8 to brush past the fixed contacts connected to the trunks leading to the connectors, each trunk comprising five conductors a_1, b_1, c_1, d_1, e_1 . During the movement of the wipers the test relay TR the circuit of which was closed at 4 by the energization of the line relay LR , tests the condition of the trunks. As soon 70 as a free trunk is reached the test relay is excited by a current flowing from the negative pole through 4, $TR, 5, w_2, c_1$, relay ER , 6 to the positive pole of the exchange battery. The relays TR and ER are energized, TR disconnects the line relay from the calling line by opening its contacts 1, 2 so that the line relay LR is deenergized and opens the turning magnet circuit at 3, 75 which results in the wipers w_1, w_2, w_3, w_7, w_8 stopping on the free trunk. By the energization of the relay TR the calling subscriber's line a, b is extended through 8 and 9 to the wipers w_1, w_2 . Through the contact 10 a part of the winding of the test 80 relay TR is short circuited which causes the potential on the test wire c_1 , to be lowered and the trunk seized by the trunk finder to appear engaged to other trunk finders searching for a free trunk. At contact 11 85 the test relay TR closes a locking circuit for itself which is independent of the contact 4 which is now open. By connecting the negative pole of the battery through contacts 34, 11 and the winding of the test relay 90 to the test wire c_2 , coming from the connectors, the calling line is made to appear engaged to all connectors through which connections to the calling line are attempted 95 to be established as will be more fully explained later.

The moment the line relay LR was energized the negative pole of the battery was connected through the contact 4 and through TR to the test wire c_2 so that the calling 100 line was made to appear engaged immediately the calling line commenced with the call, for, as will appear more clearly later, a connection can only be made with a subscriber S when the positive potential predominates on his test wire c_2 .

When the relay ER was energized in the manner described above it locked up through its contact 19 and contact 20 of RM_1 to the positive pole of battery, and closed the energizing circuit of the change-over relay CR_1 and of the release relay RR . The change over relay CR_1 is energized immediately by a current flowing from the positive pole through 7, 8, CR_1 to the negative pole. 110 But the winding of the relay RR is short circuited at first by the contact 8. A moment after the energization of ER and TR the line control relay CR receives current 115 on account of the closure of contacts 8, 9 120 125 130 135

of relay T R, this current flowing from the positive pole through C R, a_1 , w_1 , 8, a , S, b , 9, w_2 , b_1 , C R to the negative pole. The relay C R then opens the short circuit of the relay R R at 8 and closes a short circuit about the change-over relay C R₁ at 12, this relay being now deenergized whilst the release relay R R closes the stepping or measuring circuit of the connector at 16 and opens release circuit at 18.

The function of the change-over relay C R₁ is to shift or change over the stepping or measuring circuit (positive pole, 7, 14, 16, S₁), which is controlled by the line control relay C R, from the lifting magnet to the rotary magnet and then to change over the connector from its rotary action to its testing action.

The change over is accomplished at the end of each series of stepping or measuring impulses (by which the amount of movement of a switch or connector is determined) whenever the front contact 15 of the line control relay is kept closed for an appreciable period of time. It will happen in the practical working of the system that when a calling subscriber is connected by his trunk finder Fig. 1 to the next switch Fig. 2 the line control relay C R in this switch will be energized and its contact 15 closed for an appreciable time before the calling subscriber commences working his impulse transmitter I T and sending in the selecting impulses. In order to prevent a change over by this first long closure of the contact 15 the change over circuit (positive pole 7, 15, 17, O S₄, S M, negative pole) is kept open at O S₄ until this contact O S₄ is closed which does not happen until the first selecting action of the switch or connector has commenced. Therefore, when the change over relay C R₁ is deenergized by the short circuit of appreciable duration at the contact 12 of the line control relay and the contact 17 is closed by this deenergization, the change-over impulse which would flow through 7, 15, O S₄ and through the change-over magnet, is prevented by the contact O S₄ being open.

Upon the subscriber S now working his impulse transmitter I T he causes in a well-known manner a number of openings of his line loop a, b corresponding to the number of the wanted line and at each opening the line control relay C R lets its armature drop back so as to close the contact 14 and open the contact 12. The contacts 8 and 12 are so adjusted as to be hardly closed during the oscillation of the armature of C R and so that if they are closed at all the closure will only take place when the armature is in its extreme rear or front position. The contact 14 is so adjusted as to be closed rather early in the course of the travel of the armature of C R from its forward to its back

position. The closures of contact 14 result in energizations of the lifting magnet L M by current impulses from the positive pole through 7, 14, 16 S₁, L M to the negative pole of the battery, whereby the wipers w_4 , w_5 , w_6 are lifted to the contact row containing the wanted line. Current impulses also flow from the positive pole through 7, 14, 16 S₁, magnet ZM₁ of the zone switch to the negative battery pole and the brush k_1 of the zone switch is rotated as many steps as the wipers w_4 , w_5 , w_6 are raised by L M.

On account of the above-described adjustment of the contacts 8 and 12 the short circuitings of the relays C R₁ and R R during the oscillations of the armature of the line control relay are so brief in duration that these relays do not find time to release their armatures during the time the selecting impulses are being sent. Therefore the contact 16 will be kept closed and the contact 17 opened during this time. At the finish of the first series of selecting impulses the line control relay C R will keep its armature attracted steadily for an appreciable time so that the contacts 15 and 12 will be kept closed. The latter contact will short circuit and deenergize the change-over relay C R₁ and then as soon as this relay allows its armature to fall back so as to close the contact 17 a change-over current impulse will flow from the positive pole through 7, 15, 17, O S₄, which was closed the moment the wipers w_4 , w_5 , w_6 were lifted, and through the circuit changer magnet S M to the negative pole of the battery. The circuit changer magnet then moves the movable contacts S₁, S₂, S₃ into their second positions onto the contacts 29 and 30. The shifting of S₁ to 29 changes the measuring circuit over from the lifting magnet LM to the rotary magnet R M and if the contact row to which the wipers w_4 , w_5 , w_6 have been raised does not represent a nonpermissible connection the calling subscriber by now working his impulse transmitter I T a second time will cause rotary impulses to flow from the positive pole through 7, 14, 16, S₁, R M to the negative pole whereby the rotary magnet R M is caused to turn the wipers w_4 , w_5 , w_6 , round until they reach the set of bank contacts connected to the wanted line. If the contact row to which the wipers w_4 , w_5 , w_6 , have been raised represents a nonpermissible connection, the brush k_1 connected to the zone switch will have been moved onto a contact connected to the circuit of the disconnecting relay so that the moment the movable contact S₃ reaches its second position a current will flow from the negative pole through k_1 , S₃, e₁, w_8 , T R₂ to the positive pole. The relay T R₂ would then have been energized so as to disconnect the calling line from the exchange equipment. The relay T R₂ may be slow-acting and a tone

signal or any other device may be connected to the front contacts of the relay TR_2 by which the calling subscriber is notified of the disconnection.

5 The operations in establishing a talking connection had been followed up to the point where the wipers w_4, w_5, w_6 had been stepped round by the rotary selecting impulses to the fixed contacts representing the wanted line.

10 When the rotary selecting impulses cease the line control relay CR is again energized steadily and the contact 12 is closed for an appreciable time so that the contacts 17 and 15 are closed simultaneously and the circuit changer magnet SM is energized and moves the movable contacts S_1, S_2, S_3 into their third positions and closes the circuit of the test relay TR_1 through S_2 and 31. The 20 circuits belonging to the wanted line are arranged at the trunk finder in the same way as those of the calling line. Therefore if the wanted line is busy through having itself originated a call its test relay TR at its 25 trunk finder will be energized. By the shifting of contact 33 from 32 to 11 the lower end of the winding of the relay TR will be disconnected from the positive pole and connected to the negative battery pole 30 through 34. The desired line will therefore be rendered engaged and the test relay TR_1 in the connector trying to establish a connection will not be energized because both ends of its winding will be connected to the negative pole of the battery (through $S_2, 31, 21$, and 34, 11, TR, c_2 respectively).

35 If the wanted line is free its test wire (similar to c_2) will be connected through its test relay (similar to TR , Fig. 1) and through parts similar to 33, 32, OS_2 , resistance 36 to the positive battery pole and therefore, when the circuit changer contact S_2 , Fig. 2, shifts into its third position a current will flow from the negative pole 40 through $S_2, 31, 21, TR_1, w_6, c_2, TR, 33, 32, OS_2, 36$ to the positive battery pole. The relays TR_1 and TR will attract their armatures, the latter disconnecting the line relay LR of the wanted subscriber from the 45 wanted line and closing a new path from the positive pole through 35, 11 and the former connecting the ringing current source RM_3 to the wanted line through $RCR, 27, 26$ and short-circuiting a part of its winding at 50 28, thereby immediately lowering the potential on the test wire c_2 of the wanted line and rendering it engaged i. e., making it impossible for other test relays TR_1 of other 55 connectors to be energized on connecting to the same wanted line.

60 Ringing current will now flow from the ringing machine RM_3 through $RCR, 27, 26, w_4, a_2, a$, wanted subscriber's bell $b, b_2, w_5, 23$, interrupter 37 to the other pole of the ringing machine RM_3 . When the

wanted subscriber responds to the call by raising his receiver from its switchhook the ringing current flowing through the ringing control relay is strengthened sufficiently to energize this relay causing it to close its contact 22 and to energize the ringing cut-off relay RR^1 by a current which flows from the positive pole through 22, RR^1 to the negative pole of the battery. The relay RR^1 closes its contacts 24, 25 and cuts off the ringing machine RM_3 by opening its contacts 23, 26. The relay RR^1 closes a locking circuit for itself through its armature 38, this locking circuit extending from the negative pole through $RR^1, 38, OS_3$, to the positive pole and being independent of the contact 22.

70 The relay RR^1 also causes a momentary closure of the contact 50 whereby a current impulse flows from the positive pole of the exchange battery through motor magnet ZM , switch arm k_3 , contact bar s_1 , contact 50 to the negative pole. Motor magnet ZM attracts its armature and when the current impulse ceases the spring f causes the ratchet 75 to be moved a step forward thereby bringing brush k_3 on to the segment s_2 . Current will now flow from the positive pole of the exchange battery through ZM, k_3, s_2 and interrupter I_2 and the motor magnet ZM will 80 be operated so as to turn the brush k_3 and the attached brush k_2 through a circle. According to the position of the determining switch k_1 one or more of the contacts m_1, m_2, m_3 will be connected to the negative pole of 85 the battery. In moving through its cycle the delivering switch k_2 will therefore deliver through wire d_1 to the meter Z (Fig. 1) one or more current impulses according to 90 the number of contacts m which are active 95 (i. e. connected to negative battery pole.) The number of active contacts corresponds to the number of steps which the brush k_1 of the zone switch has been moved which again corresponds to the number of vertical steps which have been taken by the selector. The subscriber's meter will therefore 100 register a charge corresponding to the value of the connection and independent of the duration of the talking connection. 115

105 Returning to the operations involved in establishing a talking connection, the energization of the relay RR^1 connects the calling subscriber to the called subscriber through $a, 8, w_1, a_1, co_1, 25, w_4, a_2$, and a of the called subscriber, b, b_2 of this subscriber and through $w_5, 24, co_2, b_1, w_2, 9, b$. 110

115 When the calling subscriber replaces his receiver and thus interrupts the connection between his line limbs a and b for an appreciable period the release relay RR is 120 steadily short circuited by the contact 8 and allows its armature to drop back. The release circuit at the exchange is then closed at 18 and the release magnet RM_1 is energized. 125

gized by a current which flows from the positive pole through $O S_3$, release magnet $R M_1$ 18 to the negative pole.

The release magnet R_2 of the zone switch 5 is also energized by a current which flows from the positive pole through $O S_2$, R_2 , 18 to the negative pole and the brush k_1 , is thereby returned to its normal position. The release magnets remain energized until 10 the wipers w_4 , w_5 , w_6 return to their normal position when the off-normal switch $O S_3$ is opened. Whilst the wipers are returning to their normal position the release magnet $R M_1$ keeps a contact 21 open and thereby 15 prevents the test or busy potential being momentarily applied to the lines the bank contacts of which are touched by the wipers in returning to their normal position.

By opening a contact 20 the release magnet 20 interrupts the circuit of the relays $T R$ and $E R$. $E R$ thereupon opens the circuit of $C R_1$ at contact 7 and $T R$ closes the circuit of the turning magnet $R M$ at 38 which extends from the positive pole through I , $R M$, 39, $O S_1$, 38 to the negative pole of the battery. The turning magnet $R M$ then steps the wipers w_1 , w_2 , w_3 , w_7 and w_8 round until they reach their normal position in which the contact $O S_1$ is opened and breaks 30 the turning magnet circuit.

If a wanted line is found busy the relay $R R^1$ will not be energized and the contact 50 will not be closed. Consequently the magnet $Z M$ will not receive a metering impulse 55 and the brushes k_2 , k_3 will not be rotated. Since the brush k_1 will have been advanced to a certain row of contacts $c a$, $c b$, $c c$, the brush k_1 has to be restored to its normal position. This is done by means of the separate restoring magnet R_2 of the zone switch. Alternatively the brush k_1 may be advanced over its contact rows against the action of a spring and held in its advanced position by means of a locking device such as a pawl engaging notches in a wheel attached to the brush k_1 . When the selector shaft approaches its normal position a mechanical device on the selector shaft releases the holding pawl so that the brush k_1 is returned to its normal 45 position by the spring. In the case where a talking connection is actually established the release of the holding pawl may be accomplished by means of a cam on the brush k_2 when the delivering member has almost 50 reached its normal position.

Since the movements executed by the zone discriminating or impulse determining switch (ZM_1 , k_1) correspond to the movements of the shaft of the selector switch with 60 which the zone switch is associated, it is obvious that the determining switch may be controlled by the selector shaft and that the stepping magnet $Z M_1$ and the release magnet R_2 . Fig. 2 may be dispensed with. A 65 number of sets of contacts springs of which

each set corresponds to a certain contact row of the switch k_1 , would be arranged in the path of travel of the selector shaft and when the shaft is moved a certain distance a certain set of contacts would be affected by a projection or collar on the selector shaft. If the zone is of the kind shown in Fig. 2 and a connection is established with a subscriber in the third zone which is reached through the seventh, eighth and ninth rows of bank contacts for example, the collar or projection on the selector shaft could be arranged to close three contacts springs corresponding to the three fixed contacts $c a$, $c b$, $c c$ and to connect these springs to the negative pole 80 of the exchange battery. The contacts m^1 , m^2 , m^3 of the delivering switch would thus be connected to the negative pole of the exchange similarly as they are connected thereto by the brush k_1 of Fig. 2. 85

Of course, the selector shaft could also be made to prepare the circuit of the disconnecting relay TR_2 , which causes the calling subscriber to be disconnected from the exchange equipment whenever a non-permissible connection is attempted. 90

If the actuating circuit of the delivering switch is arranged to be closed at a contact 50 at the end of the talking connection, the circuits of the restoring magnets RM_1 of the selector switches would be arranged to be closed shortly before the impulse delivering members complete their revolution. In this way any premature disconnection of the impulse delivering switch k_2 from the meter Z 95 can be effectually prevented. 100

I claim:

1. In a telephone exchange system, a plurality of lines divided into different traffic zones, means for establishing connections between calling and called lines, toll devices normally inert operating mechanism for said devices and rendered operable upon the establishment of any connections, and means for preventing the establishment of a connection between a calling line and a called line belonging to a certain zone. 105

2. In a telephone exchange system, a plurality of lines divided into different traffic zones, a selective operable switch, means for operating said switch for establishing connections between calling and called lines, a toll device operable a predetermined number of times upon the establishment of any connection, and means for preventing the establishment of a connection between a calling line and a called line belonging to a certain zone. 115

3. In a telephone exchange system, a plurality of lines divided into different traffic zones, selectively operable switches, means for operating said switches for establishing connections between calling and called lines, toll devices, normally inert impulsive mechanism for said devices and rendered oper- 125

- able upon the establishment of any connection, and means for preventing the establishment of a connection between a calling line and a called line belonging to a certain zone 5 and the operation of said toll device.
4. In a telephone exchange system, a plurality of lines divided into different traffic zones, switching means for establishing connections between calling and called lines, a toll device operable upon the establishment of any connection to record only the value of the connection, and means controlled by said switching means for preventing the establishment of a connection between a calling line and a called line belonging to a certain zone.
5. In a telephone exchange system, a plurality of lines divided into different traffic zones, a selectively operable switch, means 10 for operating said switch for establishing connections between calling and called lines, a toll device operable upon the establishment of any connection to charge only for the character of said connection, and means controlled by said first mentioned means for preventing the establishment of a connection between a calling line and a called line belonging to a certain zone.
6. In a telephone exchange system, a plurality of lines divided into different traffic zones, connector switches, means for operating said switches for establishing connections between calling and called lines, a toll device, means controlled by said first mentioned means for preventing the establishment of a connection between a calling line and a called line belonging to a certain zone, and means for actuating said toll device only upon the successful establishment of a connection and solely in accordance with the character of said connection.
7. In a telephone exchange system, a plurality of lines, divided into different traffic zones, a selectively operable switch, means 45 for connecting a calling line therewith, operating means for said switch to establish connections between calling and called lines, a toll device operable upon the establishment of a connection for recording a charge corresponding only to the character of the connection, and means controlled by said operating means for severing the connection between a calling line and the switch operable in response to an attempted connection with a called line belonging to a certain zone.
8. In a telephone exchange system, a plurality of lines divided into different traffic zones, switching means for establishing connections between calling and called lines, a toll device operable upon the establishment of a connection between a calling and a called line through said switching means, means for generating toll charging impulses upon the establishment of said connection, and means controlled by said switching means for sever- 50
- ing the connection between a calling line and the switching means upon an attempted connection with a called line belonging to a certain zone.
9. In a telephone exchange system, a plurality of groups of lines divided into different traffic zones, a selectively operable switch, means for connecting a calling line with said switch, means for actuating said switch to select a called line by group and individual line selecting operations, a toll device operable upon the establishment of a connection between a calling and a called line through said selector for recording a charge corresponding only to the character of said connection, and means variably operable in accordance with the group selecting operation for severing the connection between a calling line and the switch.
10. In a telephone exchange system, a plurality of lines divided into different traffic zones, means including a selectively operable switch for establishing connections between calling and called lines, a variably operable toll device, means for operating said toll device a predetermined number of times upon the establishment of a connection with a line belonging to a certain zone, and means for operating said toll device a different number of times upon the establishment of a connection with a line belonging to another zone.
11. In a telephone exchange system, a plurality of lines divided into different traffic zones, switching means for establishing connections between a calling and called lines, a variably operable toll device, normally inert means for operating said toll device in a certain manner upon the establishment of a connection with a line belonging to a certain zone, and for operating said toll device in a different manner upon the establishment of a connection with a line belonging to another zone, and means for preventing the operation of said toll device if connection is attempted with a called line belonging to a certain other zone.
12. In a telephone exchange system, a plurality of lines divided into different traffic zones, means including a selectively operable switch for establishing connections between calling and called lines, a variably operable toll device associated with a calling line, normally inert means for operating said toll device in a certain manner upon the establishment of a connection with a called line belonging to a certain zone, and for operating said toll device in a different manner upon the establishment of a connection with a called line belonging to another zone, and means for preventing the operation of said toll device if connection is attempted with a called line belonging to a certain other zone.
13. In a telephone exchange system, a plurality of lines belonging to different zones,

a selectively operable switch, an impulse device, means for operating said switch in accordance with different numbers of impulses depending on the zone to which the called line belongs, a toll device variably operable only in accordance with the zones to which lines belong, and mechanism associated with said switch and variably operable in accordance with said impulses for controlling 10 said toll device.

14. In a telephone exchange system, a plurality of lines belonging to different zones, a connector switch, an impulse device associated with a calling line, means for connecting a calling line with said switch, means for operating said switch in accordance with different numbers of impulses depending on the zone to which the called line belongs, a toll device variably operable only in accordance with the zone to which the called line belongs, and a switch associated with said connector and variably operable in accordance with said impulses for controlling said toll device and the connection between a calling line and said connector.

15. In a telephone exchange system, a plurality of lines divided into different zones, a selectively operable switch arranged to connect a calling line with called lines belonging to different zones, an impulse transmitter associated with a calling line, a relay associated with said switch and responsive to said impulse transmitter, a motor magnet for said switch controlled by said relay, a toll device associated with the calling line, an impulse registering mechanism associated with said switch, means depending on the position of said mechanism for variably operating said toll device, a motor magnet 40 for said mechanism, and a circuit for said last mentioned motor magnet controlled by said relay.

16. In a telephone exchange system, a plurality of lines divided into different zones, a connector switch arranged to connect a calling line with called lines belonging to different zones, an impulse transmitter associated with a calling line, means for connecting said calling line with said switch, a relay associated with said connector and responsive to said impulse transmitter, a multi-position switch, a motor magnet for said connector, a motor magnet for said multi-position switch, a circuit including said motor magnets controlled by said relay, a toll device associated with the calling line, means depending on the position of said multi-position switch for variably operating said toll device only in accordance with the zone of the called line, another relay controlling the connection between the calling line and said connector switch, and a circuit for said other relay controlled by said multi-position switch.

17. In a telephone system, calling stations, 65 called stations, telephone lines, means comprising automatic switches for completing a connection over any of said lines, a call charging device for each calling station, a mechanism for registering selective impulses, 70 and means controlled by said mechanism for automatically operating said charging device, a predetermined number of times for each completed connection and in accordance with the character of said connection. 75

18. In a telephone system, a calling station, called station, telephone lines, means comprising a plurality of automatic switches and said lines for completing a connection between said calling station and said called 80 station, a call charging device for the calling station, a selective impulse registering device, and means automatically controlled by the subscriber at the called station for operating said call charging device under control of said selective impulse registering device, a predetermined number of times for 85 each completed connection and in accordance with the character of said connection.

19. In a telephone system, a calling station, 90 a called station, telephone lines, means comprising serially arranged automatic switches and said lines for completing a connection between said calling station and said called station, a call charging device for 95 the calling station, a selective impulse register, and means controlled by response of the subscriber at the called station for operating said call charging device under control of said selective impulse register device a 100 predetermined number of times for each completed connection and in accordance with the character of said connection.

20. In a telephone system, a calling station, 105 a called station, telephone lines, a plurality of automatic switches for completing a connection from said calling station to said called station and including certain of said telephone lines, a call charging device for each calling station, selective numerical impulse storing means, and means controlled 110 by response of the subscriber at the called station for operating said registering device under control of said storing means, a predetermined number of times for each completed connection according to its value. 115

21. In a telephone system, a calling station, a called station, means comprising telephone lines and serially arranged automatic switches for completing a connection from the calling station to the called station, a call charging device for the calling station, a device for storing selective impulses transmitted to one of said switches, and means controlled both by the subscriber at the calling station and by the subscriber at the called station for operating said call charging device a predetermined number of times 125

under control of said storing device, according to the telephone lines in use in the completed connection.

22. In a telephone system, a calling station, a called station, telephone lines and automatic switches for interconnecting said stations, a call registering device for the calling station, call register controlling mechanism accessible in common to both 10 said stations and comprising a numerical register, and means controlled by the subscriber at an interconnected called station for rendering said mechanism effective to cause said device to be operated a predetermined number of times in accordance with the telephone lines used in the connection between the calling and called stations.

23. In a telephone system, calling stations, called stations, telephone lines and automatic 20 switches for interconnecting any calling and called stations, a call charging device for each calling station, controlling mechanism for said device comprising a numerical selective impulse storing device, means controlled 25 by the subscriber at an interconnected calling station for variably adjusting said mechanism to cause said device to be operated a predetermined number of times in accordance with the value of the connection between the calling and called stations.

24. In a telephone system, calling and called stations, telephone lines and serially arranged automatic switches for interconnecting any two of said stations, a call registering device for each station, numerical impulse storing mechanism for controlling said device and adapted to be variably set under control of the subscriber at a calling station, said setting also corresponding to the value 35 of the connection between said calling station and the said called station, and means controlled by the subscriber at the called station for rendering said mechanism effective to operate said device a predetermined number of times.

25. In a telephone system, calling and called stations, telephone lines and serially arranged automatic switches for interconnecting any two of said stations, at least one 50 of said switches being a numerical switch, a call registering device, mechanism comprising a selective impulse register for controlling said device and adapted to be variably set under control of the subscriber at the calling station, said setting also corresponding to the value of the connection between said calling station and said called station, and means controlled by the subscriber at the interconnected called station for rendering said mechanism effective to operate said device a predetermined number of times corresponding to the setting of said mechanism.

26. In a telephone system, calling stations, called stations, means comprising telephone 60 lines and automatic switches for completing

a connection from any one of said calling stations to any one of said called stations the value of said connection varying in accordance with the telephone lines in the completed connection, a call charging device 70 for each calling station, impulse registering and controlling mechanism for, and accessible in common to said devices, means under control of the subscriber at a calling station for variably setting said mechanism, said 75 setting corresponding to the value of the connection between the calling and called stations, and means controlled by the subscriber at the called station for rendering said mechanism effective upon said device to cause the same to be operated a predetermined number of times corresponding to the setting of said mechanism.

27. In a telephone system, calling stations, called stations, means comprising telephone lines and automatic switches for completing a connection from any one of said calling stations to a desired one of said called stations the value of said connection varying according to the telephone lines in the completed connection, a call charging device for each calling station, step-by-step numerical register mechanism accessible in common to each of said devices, means under control of the subscriber at a calling station for variably setting said mechanism, said setting corresponding to the value of the connection between the calling and called stations, and means controlled by the response of the subscriber at the called station for rendering said mechanism effective upon said device to operate the same a predetermined number of times corresponding to the setting of said mechanism.

28. In a telephone system, a calling line, a 105 meter for said line, an automatic switch accessible to said line, a meter controlling mechanism associated with said switch, a plurality of called lines accessible to said switch, means for extending a connection 110 from the calling line to said automatic switch, means for then operating said switch to seize any one of said called lines, and means for operating said mechanism a predetermined number of times before certain 115 of said called lines are connected with and means for operating said mechanism a different number of times before others of said lines are connected with, and a circuit for said meter controlled by said mechanism.

29. In a telephone system, a calling station, called stations, means comprising telephone lines and automatic switches for completing a connection from said calling station to a desired one of said called stations, the value 125 of said connection varying according to the particular called station desired and the telephone lines used in the connection, a call charging device associated with each completed connection, a called station designa- 130

tion registering mechanism for controlling said device, an operating magnet for said registering mechanism, means for operating said magnet a number of times when said completed connection is of one value and a different number of times when the completed connection is of a different value.

30. In a telephone system, calling stations, called stations, means comprising telephone lines and serially arranged automatic switches for completing connections of different values from said calling stations to a desired one of said called stations, a call charging meter for each calling station, a called station designation registering mechanism for controlling the operation of said meter, said mechanism being variably operated according to a portion of the numerical designation of a desired called station, and means for causing said mechanism to operate said meter a certain number of times corresponding to the value of the connection between the calling and called stations.

31. In a telephone system, a calling station, called stations, means comprising telephone lines and serially arranged automatic switches for completing a connection from said calling station to a desired one of said called stations, a call charging device for each station, numerical selective impulse register mechanism for controlling the operation

of said device and adapted to be operated a variable number of times during the completion of the connection, and means responsive to the completion of the connection for causing said mechanism to operate said device a number of times which is proportionate to the number of times said mechanism was operated during the completion of the connection.

32. In a telephone system, a calling station, called stations, a meter for the calling station, means comprising serially arranged automatic switches for extending a connection from said calling station toward a desired one of said called stations, telephone lines accessible to one of said switches, means for operating said one of said switches to further extend the connection over one of said lines, a meter controlling device associated with said one of said switches, said device adapted to be adjusted during the extending of the connection in accordance with the value of the extended connection, and means controlled by the response of the subscriber at the called station for causing said meter to be operated according to the adjustment of said device.

In testimony whereof I have signed this specification.

Frau ELSE HECHT, geb. HEIMANN,
Administratrix of Georg Heimann, Deccascd.
